Design No. 14,228, dated August 21, 1883.

UNITED STATES PATENT OFFICE.

ACHILLE MONIOT, OF PHILADELPHIA, PENNSYLVANIA, ASSIGNOR TO SAMUEL ALLEN & CO., OF SAME PLACE.

DESIGN FOR AN UPHOLSTERY FABRIC.

SPECIFICATION forming part of Design No. 14,228, dated August 21, 1883.

Application filed July 20, 1883. Term of patent 3½ years.

To all whom it may concern:

Be it known that I, ACHILLE MONIOT, a citizen of the United States, residing at Philadelphia, in the county of Philadelphia and State of Pennsylvania, have invented and produced a new and original Design for a Pattern to be Inwrought in Two-Ply Upholstery Tapestry or Damask, woven with two warps and two wefts, in such colors or shades of materials as to may be desired; and I do hereby declare that the photographic print accompanying this specification conveys to any one skilled in the art of weaving upholstery tapestry and damask a clear understanding of the same, and is sufficient to enable such person to use my invention.

What I claim as my invention, and desire to secure by Letters Patent, is—

The design for upholstery tapestry or damask, as shown in the photographic print accompanying this specification.

ACHILLE MONIOT.
